UNITED STATES PATENT OFFICE.

CHARLES EDWARD TIEDEMAN, OF GLOVERSVILLE, NEW YORK.

CATAPULT AND PROJECTILE THEREFOR.

1,405,075.

Specification of Letters Patent. Patented Jan. 31, 1922.

Application filed May 7, 1921. Serial No. 467,754.

To all whom it may concern:

Be it known that I, CHARLES E. TIEDEMAN, a citizen of the United States, and a resident of Gloversville, in the county of Fulton and State of New York, have invented certain new and useful Improvements in Catapults and Projectiles Therefor, of which the following is a specification.

My invention relates to catapults and the purpose of my invention is the provision of a catapult of extremely simple, durable and inexpensive construction, which is manually operable to impel a ring-like projectile in different velocities and in such manner as to maintain the projectile in up-right position during flight.

It is also a purpose of my invention to provide a projectile constructed to permit of its looping an attenuated target, and provided with a penetrating or adhesive striking surface to cause its adherence to any target having a roughened surface at a point at which it strikes the surface.

I will describe one form of catapult and one form of projectile, each embodying my invention, and will then point out the novel features thereof in claims.

In the accompanying drawings:

Figure 1 is a view showing in side elevation one form of catapult embodying my invention.

Figure 2 is a view showing in side elevation the catapult shown in Figure 1 with the projecting member thereof in acting position.

Figure 3 is a view showing in end elevation the catapult shown in Figure 1.

Figure 4 is a detailed perspective view of one form of projectile embodying my invention.

Figure 5 is an enlarged detail perspective view of the abutment member comprised in the catapult shown in the preceding views.

Similar reference characters refer to similar parts in each of the several views.

Referring specifically to the drawings, my invention in its present embodiment consists of a projecting member designated generally at P, and an abutment member A slidably receiving the projecting member and operatively connected thereto by means of an elastic actuating member E. The projecting member P comprises in the present instance a rod 15 at the forward end of which is formed a head 16 tapered in diameter toward its forward end and provided at its

rear end with an annular flange 16^a. Formed at the rear end of the rod 15 is a tapered extension 17, the confronting end of which exceeds in diameter that of the rod 15 so as to provide a shoulder which is covered by a band 18 formed of felt or any other material which will effectively absorb the shock imparted to the extension when actuating the catapult. The rear end of the extension 17 is provided with a knob or handle 19 having formed therein a slot 19^a.

The abutment member A comprises a body 20 of substantially double conical form with the two cones arranged in opposed relation and separated by an annular channel 21. The body 20 is formed with an axial bore 22 which is of a diameter to slidably receive the rod 15. Communicating with the channel 21 at diametrically opposed points are radially extending slots 23.

The elastic actuating member E comprises in the present instance one or more rubber bands which in their applied position have one end inserted within the channel 21 and then passed through the slots 23, their opposite end being trained through the slot 19^a of the handle 19. In this position of the bands they are held under tension so that the projecting member is at all times urged through the projecting member A in the direction of the head 16.

In Figure 4, I have shown one form of projectile designated at J adapted to be used in conjunction with the catapult shown in the preceding views. The projectile J in the present instance comprises an annulus or ring preferably formed of fabric and in such manner as to provide at its opposite edges penetrating portions 24. In practice, the projectile J is formed of linen or cotton which is impregnated with some stiffening substance so as to maintain the ring like form, with the threads of the fabric projecting from the opposite edges of the annulus to provide the penetrating portions 24. The purpose of the penetrating portions 24 is to induce the projectile to adhere to the roughened surface of a target formed of flannel or similar cloth so that when it is projected against the target it will adhere to the same point thereon at which it strikes the target.

In the operation of the catapult, the abutment member is firmly gripped with one hand and the handle 19 with the other, the projectile being placed upon the head 16 in the manner shown in Figures 1 and 2. By

holding the abutment member A and re-tracting the projecting member from the position shown in Figure 1 to that shown in Figure 2, the elastic member E is put under 5 such tension that when the handle is released the projecting member will be rapidly impelled forwardly until striking the abutment member A when such movement is suddenly checked. Under this action of the 10 projecting member, the projectile J is hurled forwardly from the head 16 and in such manner that it is maintained in upright position, that is to say, the path of movement of the projectile is at right angles to the 15 plane of the projectile. With the projectile moving in upright position, it will be clear that when it is directed to a cloth target one penetrating portion 24 or the other will strike the surface of the target and thus 20 cause its adherence thereto so that the accuracy of the shot can be readily determined. Because of the ring-like form of the projectile it can be used in ringing stationary objects which is another way of testing the 25 skill of the user.

Although I have herein shown and described only one form of catapult and one projectile, each embodying my invention, it is to be understood that various changes and 30 modifications may be made herein without departing from the spirit of the invention or the spirit and scope of the appended claims.

What I claim is:

- 35 1. A catapult comprising, a projecting member including a rod, a head on one end of the rod, a shoulder formed on the opposite end of the rod, a shock absorbing element on said shoulder, an abutment member slidably mounted on the rod, an elastic member 40 associated with the projecting and abutment members to normally urge said rod so that said element engages the abutment member, and a projectile removably fitted on said 45 head.
2. A catapult comprising, a projecting member including a rod, a flanged and tapered head formed on one end of the rod, an extension formed on the opposite end of 50 the rod, an abutment member slidably fitted on the rod and confined thereon by said head and extension, said abutment member being

formed with a channel and slots communicating with the channel, an elastic member trained through portions of the channel and 5 said slots and engaging said extension for urging the projecting member so as to cause said extension to engage the abutment member, and a ring-like projectile mounted on said head.

60 3. In combination, a catapult comprising, a projecting member, an abutment member for supporting the projecting member for reciprocating movement, an elastic member for yieldingly maintaining the projecting 65 member in one extreme position with respect to the abutment member, and a projectile removably carried by the projecting member, said projectile being of ring-like formation and having penetrating edges.

70 4. A catapult comprising a projecting member including a rod, a flanged and tapered head formed on one end of the rod, a tapered extension formed on the opposite end of the rod and of a diameter to provide 75 a shoulder at the junction of the rod and extension, a shock absorbing element positioned on the shoulder, a slotted handle formed on the other end of the extension, an abutment member slidably mounted on 80 said rod and having a channel with slots formed therein, elastic bands trained through the slots and channel of the abutment member and through the slot of said handle, and a ring-like projectile removably 85 fitted on said head.

5. A projectile for catapults comprising, an annulus having its opposite edges formed with portions which are adapted to penetrate the cloth target for inducing the projectile to adhere to the surface of the target.

90 6. A projectile for catapults comprising an annulus formed of fabric the threads of which are exposed at the opposite edges of the annulus to provide target penetrating 95 portions.

7. A projectile for catapults, comprising an annulus formed of fabric and impregnated with a stiffening substance, with the threads of the fabric exposed to the opposite 100 edges of the annulus to provide penetrating portions.

CHARLES EDWARD TIEDEMAN.
